SYSTEM FOR TRANSMITTING
INTELLIGENCE

Walter S. Lemmon, New York, N. Y., assignor, by
mesne assignments, to International Business
Machines Corporation, New York, N. Y., a cor-
poration of New York

Application March 2, 1935, Serial No. 8,978

4 Claims. (Cl. 178—52)

This invention relates to the transmission of intelligence either through wired circuits or by radio, and more particularly to that type of transmission wherein the signal impulses produced by the operation of a typewriter or like machine, are so timed in their transmission that they may be picked up and differentiated on a time basis by the receiver for causing the appropriate characters to be reproduced.

10 In systems of the kind referred to it is the practice to provide in the sender a multiplicity of circuits, each individual to a particular character, and each including a contact segment of a commutator, together with a rotary collector adapted to engage each commutator segment at a predetermined point in its cycle of operations. The arrangement is such that an actuation of a key of the transmitting machine causes the circuit individual to that key to be charged and 15 stored with electrical energy. When the rotary collector engages the commutator segment included in that particular circuit a discharge takes place causing current to flow, and this discharge is inductively transmitted into the output circuit 20 of the sender.

The receiver similarly includes a receiving distributor which comprises a rotary arm or contact member and a commutator over which the rotary distributor arm runs. When the signal comes 25 through it is transmitted through the particular commutator contact which is at that instant engaged by the rotary distributor and hence produces an actuation of a signal character key in the receiving typewriter associated with the circuit of that particular contact.

It is important in such a system that the sending collector and the receiving distributor be operated synchronously and in phase with one another, and to this end it is desirable that the 30 motors for operating them be alike and that the operating current supplied to the motors be exactly the same in character.

It is accordingly a feature of the present invention to utilize the ordinary alternating line current such as the 60 cycle current commonly supplied by electric light and power companies or obtained from local generators for operating the motor of the transmitting collector, and at the same time to transmit a portion of said current 35 with the signal impulse to the receiver and there to detect and amplify this alternating current component for driving the motor of the receiving distributor.

It is a further feature of the invention to provide suitable filtering and amplifying means in a

branch circuit of the receiver for amplifying the signal impulses and transmitting them to the writing instrumentalities while suppressing the alternating current component in the branch circuit.

Other objects and advantages will hereinafter appear.

In the drawings forming part of this specification,

Figure 1 is a diagrammatic view illustrating 10 the transmitting and receiving apparatus of the system, and

Figure 2 is a diagrammatic view illustrating certain features of the transmitter in greater detail than Figure 1.

An alternating current generator 1 supplies alternating current through line conductors 2 and 3, and thence through a suitable switch 4, to a circuit comprising a conductor 5, a primary transformer coil 6, and a conductor 7. Branch 20 conductors 8 and 9 are connected to the conductors 5 and 7, respectively, and run to the terminals of a motor 10 which, through its output shaft 11, drives a rotary collector arm 12 at predetermined speed.

The collector arm 12 is connected at its inner end to a conductor 13. The outer end of the collector arm 12 runs upon contacts 14 and 15 of a stationary commutator 16. The conductor 13 is connected to a primary transformer coil 17 30 and the coil 17 in turn is connected to a conductor 18. The conductor 18 is connected through a multiplicity of parallel wires 19 to condensers 20 each of the wires 19 running to one terminal of one of the condensers. The opposite terminal of each condenser 20 is connected through a switch arm 21 which is normally in contact with a conductor 22 running to one of the segments 14 of the commutator 16. The condensers are normally discharged and hence the 35 circuits which are successively completed through the condensers by the running of the distributor arm 12 upon the contacts 14 are dead circuits except when one of them has been energized.

Each condenser is adapted to be charged by the actuation of a particular type key or other operating instrumentalities of the transmitting typewriter 23. When a key of the typewriter is depressed one of the switches 21 (associated exclusively with that key) is moved away from the terminal of the associated conductor 22 and into contact with the terminal of an associated conductor 24. This closes a circuit for charging the condenser 20 individual to that switch, such cir- 45

cuit comprising a conductor 25 connecting the conductor 18 to one terminal of a battery 26, and a conductor 27 connecting all of the conductors 24 to the opposite terminal of the battery. It will be understood, of course, that the battery 26 might be, and in practice frequently would be, replaced by a rectifier supplied with line current from the conductors 2 and 3.

When a key is actuated the associated switch 21 is moved over into circuit with the conductor 24 momentarily and is immediately returned automatically by a spring, into engagement with the terminal of the associated conductor 22. The momentary engagement of the switch with the conductor 24 is effective to charge the associated condenser but the condenser cannot be discharged until the distributor arm 12 wipes across the segment or contact 14 which is in circuit with that particular condenser. When this occurs the condenser is discharged and a signal impulse is caused to flow through the primary winding 17.

The alternating line current flowing through the primary winding is inductively transmitted into a secondary circuit 28 through a secondary winding 29, and the signal impulses which flow through the primary winding 17 are inductively transmitted into the secondary circuit through a secondary winding 30. The current thus induced in the secondary circuit is fed into a modulator 31 and is there impressed upon a carrier current generated by an oscillator 32 and broadcast from an antenna 33.

In order to guard against inductive transmission of the alternating line current into the circuits of the condensers 20 through the coils 30 and 17 as primary and secondary, respectively, provision is desirably made of a resonant shunt circuit 34 between the conductors 13 and 18, said circuit comprising an inductance 35 and a condenser 36, whose characteristics are such that the shunt circuit will short circuit any alternating current of line frequency which may be present.

In addition to the alternating line current and the signal impulses which are transmitted, it is desirable that a phase control impulse be transmitted at a predetermined point in each cycle and to this end the commutator contact 15 is provided. A conductor 37 connects the conductor 27 and hence the battery to contact 15. It will seem that each time the arm 12 engages the contact 15 a circuit is closed through the battery and the primary coil 17 causing a phase control impulse to be transmitted. This occurs once in each revolution, and at a predetermined point.

The receiver comprises an aerial 38 and a ground 39 forming parts of a radio receiving set 40 of conventional design. In this receiving set the received energy may be amplified and the current of line frequency as well as the signal and phase control impulse may be detected. The output circuit 41 of the receiving set 40 includes a primary winding 42 which is inductively coupled to secondary windings 43 and 44 of separate circuits 45 and 46. The circuit 45 is a motor operating circuit and is supplied with received and amplified alternating current impulses identical in character with the alternating current impulses which drive the motor 10 of the transmitter. This current in the circuit 45 is used to drive a motor 47 which, through its output shaft 48, drives the receiving distributor 49 and phase control contact arm 50. The motor 47 is exactly like the motor 10, and since the current supplied

to both motors is identical in character the tendency of the two motors is to operate identically as to speed.

The circuit 46 is designed to segregate the signal and control impulses from the alternating current and to amplify them and transmit them to the receiving typewriter. To this end the circuit includes a filter 51 to suppress current of the known frequency of the alternating current received, and an amplifier 52. A conductor 53 connects the amplifier with the inner ends of the arms 49 and 50. The arm 49 runs in engagement with contact segments 54 of a stationary commutator 55 and each contact segment 54 is connected through a conductor 56 to operate a particular type bar or other operating instrumentality of the receiving typewriter. After passing through the receiving typewriter the current from all of these conductors 56 passes back to the amplifier through a conductor 57. The operating and phase control impulses are all identical in character, and are distinguished from one another solely by the period in the cycle of the sender during which they are respectively transmitted. It is necessary, therefore, to make provision for securing and maintaining phase correspondence between the sender and distributor in order to cause a received impulse to operate the particular type bar or other instrumentality of the receiving typewriter which it is intended to operate. To this end provision is made of phase control means of the same kind as illustrated in my pending application Serial No. 684,362, filed August 9th, 1933, for Synchronizing system.

This mechanism may be described briefly as follows: The conductor 53, as has been mentioned, is always connected to the inner end of arm 50 and to the inner end of arm 49. The phase control impulse, transmitted whenever the arm 12 of the transmitter engages contact 15, occurs once in each cycle and at the same point in each cycle. When the sender and receiver are first coupled they will presumably be out of phase correspondence. No signalling impulses are transmitted until a sufficient interval has elapsed to permit phase correspondence to be secured. The arm 50 runs upon a ring segment 58 and contacts 59, 60, and 61. If the first signal impulse is transmitted through the ring 58 it is caused to pass through a conductor 62, a switch arm 63, a conductor 64, a conductor 65, an advancing electromagnet 66, and a conductor 67, to the conductor 57 which runs back to the amplifier. The arms 49 and 50 are driven from the shaft 48 through differential mechanism (not shown) and each time that the electromagnet 66 is energized it operates a pawl and ratchet device for advancing the arms 49 and 50 one contact space of the commutator 55 relative to the shaft 48. As the operation continues one of these adjusting steps will be applied in each revolution until the arm 50 has advanced to a point where it will no longer engage the contact ring 58 at the moment of reception of the control impulse but will engage the contact 61. The current now flows through the contact 61 and conductor 65 to the advancing electromagnet, so that the next impulse will be received through the contact 60, the condition desired.

The current now flows from the contact 60 through a conductor 68, an electromagnet 69, and a conductor 70 to the conductor 67. The switch 63 constitutes the armature of the electromagnet 69 and it is pulled away from engage-

ment with the terminal of conductor 62 when the electromagnet 69 is energized to open-circuit the ring segment 58. A retarding device 70, which may be a dashpot, is connected to the 5 switch 63 to cause it to act slowly so that the switch 63 does not return to engagement with the terminal of conductor 62 for a plurality of cycles of the arm 50. The control impulses should now continue to come in on the contact 10 60, which produces no adjusting step, and the ring segment 58 is held continuously open circuited, and ineffective. The apparatus is now ready for the transmission of signal impulses since the transmission of signal impulses can 15 not now result in the production of adjusting steps.

Should a condition occur tending to disturb the synchronous and in-phase relation of the arm 50 with reference to the arm 12 of the transmitter, an adjusting step will immediately occur either in an advancing or retarding direction to restore phase correspondence. If the arm 50 has lagged the control impulse will be again transmitted through the contact 61 and an advancing step will immediately be applied to restore phase correspondence. If the arm 50 on the other hand has advanced away from phase correspondence the control impulse will pass through the contact 59 thence through a conductor 71, a retarding electromagnet 72, and conductor 73 to conductor 67. This will immediately apply a backward adjusting step to restore phase correspondence. Switch 63 acts slowly enough to permit these momentary deviations 35 without permitting the switch 63 to be closed.

I have described what I believe to be the best embodiments of my invention. I do not wish, however, to be confined to the embodiments shown, but what I desire to cover by Letters 40 Patent is set forth in the appended claims.

I claim:—

1. In a system for transmitting intelligence, in combination, a sender comprising a sending machine having a keyboard, each key being adapted when operated to cause the transmission 45 of a signal impulse, means comprising a rotary collector and a commutator for allotting to each key a definite period in the cycle of rotation, means in the sender for initiating a phase control impulse at a predetermined point in each cycle, a motor for driving the collector at uniform speed, a source of alternating current, means connecting said source to drive the motor, an output circuit means for transmitting the alternating current and the signal and control impulses 55 into the output circuit, and a receiver comprising electrical receiving and amplifying equipment, a receiving machine comprising printing instrumentalities, a commutator and a rotary distributor for causing the received signal impulses to operate the printing instrumentalities selectively in accordance with the timing of the received signal impulse, a motor for operating 60
- the distributor, means for transmitting the received and amplified alternating current to operate the receiver motor, and means for transmitting the received signal impulse exclusive of the alternating current, through the distributor to the several printing instrumentalities, and means responsive to the reception of the control impulse in all positions of the distributor other than that representing phase correspondence for automatically applying one or more adjusting 5 steps to the receiving distributor for stepping the same into phase correspondence with the sending collector. 10
2. In a system for transmitting intelligence, in combination, a sender comprising a sending machine having a keyboard, each key being adapted when operated to cause the transmission of a signal impulse, means comprising a rotary collector and a commutator for allotting to each key a definite period in the cycle of rotation, 15 means in the sender for initiating a phase control impulse at a predetermined point in each cycle, a motor for driving the collector at uniform speed, a source of alternating current, means connecting said source to drive the motor, an output circuit, means for transmitting the alternating current and the signal and control impulses into the output circuit, and a receiver comprising electrical receiving and amplifying 20 equipment, a receiving machine comprising printing instrumentalities, a commutator and a rotary distributor for causing the received signal impulses to operate the printing instrumentalities selectively in accordance with the timing of the received signal impulse, a motor for operating the distributor, means for transmitting the received and amplified alternating current to operate the receiver motor, and means for transmitting the received signal impulse exclusive of the alternating current, through the distributor to the several printing instrumentalities, and means responsive to the reception of the control impulse in all positions of the distributor other than that representing phase correspondence for automatically applying one or more adjusting 25 steps to the receiving distributor for stepping the same into phase correspondence with the sending collector. 30
3. The invention set forth in claim 1 in which the means for transmitting the alternating current and signal and control impulses comprises inductive means. 35
4. The invention set forth in claim 1 in which the means for transmitting the received signal impulse exclusive of the alternating current through the distributor comprises a transmitting circuit having a filter incorporated therein for filtering out current of the known frequency of 40 the motor operating current. 60
